UNITED STATES PATENT OFFICE.

EDWARD HAYES, OF LYNN, MASSACHUSETTS, ASSIGNOR OF THREE-FOURTHS
TO JAMES T. LENNOX, JOHN J. LENNOX, AND THOMAS DOWLING, ALL
OF SAME PLACE.

LEATHER-STAKING MACHINE.

SPECIFICATION forming part of Letters Patent No. 447,180, dated February 24, 1891.

Application filed July 9, 1889. Renewed January 31, 1891. Serial No. 379,790. (No model.)

To all whom it may concern:

Be it known that I, EDWARD HAYES, of 5
Lynn, county of Essex, and Commonwealth
of Massachusetts, have invented a certain Im-
5
provement in Leather-Staking Machines for
Curriers' Use, of which the following, taken
in connection with the accompanying draw-
ings, is a specification.

This invention relates to that class of ma-
10 chines used by curriers for "sleeking," soft-
ening, or "staking" leather, and the nature
thereof is hereinafter fully described, and
pointed out in the claim.

In the accompanying drawings, Figure 1 is
15 a side elevation of the machine embodying
my invention. Fig. 2 is an elevation of a
cross-section on line 2 2 of Fig. 1. Fig. 3 is
an elevation of a longitudinal vertical sec-
tion of the machine shown in Fig. 1.

20 The working parts of the machine are
mounted upon a suitable frame-work, which
is designated in the drawings by the letter B.
To that end longitudinal ways a, Fig. 2, are
secured to the frame-work and support the
25 members b e. Said members are connected
by a hinge or knuckle joint E, and that por-
tion of the knuckle which fixes to the mem-
ber e is made with grooves to receive the said
ways a a to the end that a longitudinal re-
30 ciprocating movement may be imparted to
the said member e along said ways. The mem-
ber b travels with the member e longitudi-
nally, but it also has a vertical reciprocating
movement by tilting on the joint E, which
35 movement is imparted by mechanism de-
scribed hereinafter.

The longitudinal movement aforesaid is
imparted to the members e b by means of a
mechanism comprising the wheel A and pit-
40 man H. To that end a suitable driving-power
is attached to the wheel A and is transmis-
ted to said members through the pitman H.
The pitman is for that purpose connected at
45 one end with a crank-pin f and at the other
end with the pin h, (see Fig. 3,) composing the
fulcrum of knuckle-joint E. The crank-pin
f is made adjustable toward and from the
center of wheel A, so as to give any desired
length of longitudinal movement. The wear

incident to pitman H is compensated for by 50
the tongues and wedges arranged (not shown)
in the mechanism in the usual manner.

Attached to the pitman H are brackets N,
which support a pin 4, Fig. 3, that operates
in a longitudinal groove 5 of the lever 6. Said 55
lever 6 is connected with the member b by a
pin 7, on which the member is allowed to turn
loosely. Said lever is further provided with
a pin 8, which extends from its bottom end
into a cam-groove 9, cut in the member e. 60
This arrangement causes the member b to be
tilted on its joint E whenever the wheel A is
made to turn round. The member b is pro-
vided on its end with a wheel 10, preferably
composed of rubber, and a knife 12, composed 65
of wood, in the usual manner. The member
e supports knives 13 and 14, which are mount-
ed on a hinged plate 15, to the end that the
knives may be adjusted vertically relatively
to the wheel 10. Said vertical adjustment is 70
obtained through thumb-screw 16, arranged
as shown.

In operating this machine the workman
holds the hide or leather outstretched in his
hands, and as the members open sufficiently 75
to permit it he moves the leather in between
the knives and wheel 10 and holds it there,
while the said members b e are moved verti-
cally and longitudinally, as before described,
to perform the staking operation. 80

The operation of the parts more particularly
is as follows: Supposing the disk to turn and
carry the pin f to its lowest point, the pit-
man H will be tilted and assume a down-
wardly-inclined position from the pin h to the 85
pin f. During this movement the pin 4 works
in the slot 5, and the vertical movement of
said pin is without effect on the member b;
but its lateral movement due to the tilting of
the bracket N toward the disk will cause the 90
pin to bear against the wall of the slot and
tilt the lever 6 on its pivot, causing the lower
end to move forward and the pin 8 to ride in
the lower part of the slot, which of course
draws downwardly the lever 6 and operates 95
the member b. In the rise of the pitman H
the lever 6 is tilted to the position shown, the
pin 8 bearing in the high part of the groove,

and causing the forward part of member *b* to move toward the member *e*.

Having thus described my invention, I claim—

5 In combination, the frame, the member *e*, the pivoted member *b*, the staking devices on said members, the pitman *H* for reciprocating the said members, and means for operating the member *b* on its pivot, consisting of a piv-

oted lever *6*, pivotally connected to the pitman and to the member *b*, substantially as described.

Signed at Lynn this 25th day of June, A. D. 1889.

EDWARD HAYES.
